DESIGN FOR A TIRE

William P. MacKusick and James N. Wyant,
Akron, Ohio, assignors to Wingfoot Corpora-
tion, Akron, Ohio, a corporation of Ohio

Application May 15, 1945, Serial No. 119,553

Term of patent 14 years

(Cl. D90—20)

To all whom it may concern:

Be it known that we, William P. MacKusick and James N. Wyant, citizens of the United States, residing at 53 Hawthorn Avenue and 785 Crestview Avenue (respectively), in the city of Akron, county of Summit, and State of Ohio, have invented a new, original, and ornamental Design for a Tire, of which the following is a specification, reference being had to the accompanying drawing, forming part thereof.

Fig. 1 is a perspective view of a tire showing our new design;

Fig. 2 is a plan view of a portion of the tire; and
Fig. 3 is a cross-sectional view taken on the line 3—3 of Fig. 1.

We claim:

The ornamental design for a tire, as shown.

WILLIAM P. MACKUSICK.
JAMES N. WYANT.
